WELT PRESS

Otto Jacobus, Olean, N. Y.

Application July 18, 1940, Serial No. 346,214

5 Claims. (Cl. 12—33)

This invention relates to a welt press for attaching the sole of a shoe to the welt and upper structure by means of cement. The cementing method has largely supplanted the old practice of sewing or pegging the sole in place, but it is attended with certain difficulties of applying pressure to clamp the sole to the welt along the edge of the former in a smooth and tight fashion without permitting curling or warping of the welt where it is cemented to the sole.

The object of the present invention is to provide an apparatus for doing this work smoothly and conveniently and to make a firm engagement between the parts, and the apparatus includes or comprises a flat chain which is thin enough to fit in the crease between the upper and the welt, to which chain pressure is applied by means of a plurality of clamps or other tensioning devices, which are or may be mounted on the base or support upon which the shoe is placed and which have fingers or parts which press against the chain at a plurality of places along and around the same and press the welt smoothly against the sole along the whole length of the welt, and holds it in this relation until the cement is hardened.

The device may be used either with or without a shoe press. That is an ordinary shoe press may be used to clamp the work to the bed or support if desired, but practically it has been found unnecessary.

The chain is arranged along around the welt and can be bent to fit the contour or angularity of the welt at all points. The chain is made of small thin metal links pivoted together, and may be provided with barbs to stick into the welt and hold the chain in place.

The flat faces of the links, where they contact with the welt, are level or in the same plane, so that they bear against the welt practically the whole length thereof.

The apparatus may be used or fitted for use on various kinds of shoes, since the chain can be bent according to the shape or outline of the shoe, whether large or small, wide or narrow.

The clamps are also adjustable to suit the work, so as to bear upon the chain in all positions.

With this preliminary explanation, one form of the invention is illustrated in the accompanying drawing in which:

Figure 1 is a sectional elevation of the press;

Figure 2 is a plan view thereof;

Figure 3 is a plan of the chain;

Figure 4 is a detail of the chain in edge view;

55 and

Figure 5 is an edge view of a modified form of chain.

Figure 6 is a detail of a modification.

Referring specifically to the drawing, 6 indicates the work or shoe to which the sole 7 is to be applied, the welt being indicated at 8. The shoe is mounted or rests upon a support such as a rubber pad 9 held within a base frame or box 10.

The chain is indicated at 11, and when the job is set up this chain is fitted upon or in the crease above the welt 8. It will be noted that the chain comprises a series of thin flat links connected by pivots 12, so that it may be bent to conform to the contour or outline of the welt, 15 and it is capable of being adjusted to fit any shape or size of shoe. Preferably the links which occupy the toe position are shorter than those at the sides so that the chain may be bent to a sharper angle around the toe. Also the 20 links are preferably provided with barbs or points 13 which when the chain is applied to the welt penetrate the latter and so hold the chain in position.

The form of chain shown in Figures 3 and 4 25 consists of off-set links, the ends of which lap over and under each other where they are pivoted together, as clearly appears in Figure 4. This gives a sufficiently flat surface for the intended purpose, but may be modified in various ways. 30 For example, the chain shown in Figure 5 consists of top and bottom links 11a and 11b which are straight and lap where they are pivoted together. This gives a pressure surface which is somewhat more continuous than the form 35 shown in Figure 4.

As stated this chain is fitted to and pressed down upon the welt, clamping it against the edge of the sole, and the pressure may be applied by any kind of clamps or pressure devices suitable for the purpose. I have shown clamps arranged around the periphery of the base or supporting block 10, each clamp comprising a bolt 15 extending loosely through a hole in the side wall of the base and carrying an adjustable block 45 16 under a wing nut 17, by means of which the pressure is applied. The block 16 is bored vertically to pass the bolt and has an extension 19 which is tapped horizontally to receive a thumb screw 18 extending into the extension 19 on the 50 block to clamp in position an adjustable finger or bar 20, the inner end of which is bent down as indicated at 21 to bear against the upper surface of the chain. It will be understood that the finger 20 may be moved in or out, or the block 55

- may be turned, to set the end 21 of the finger in proper position to bear against the top of the chain, and after being set in position the pressure is applied by turning down the wing nut 17 5 against the block 16, carrying the block and finger downwardly to press upon the chain with the necessary pressure to clamp the welt and the edge of the sole together, the rubber pad 9 giving whatever cushion effect may be necessary.
- 10 Obviously other kinds of clamps or tension devices may be used to do the work described, and it will be noticed that by using a plurality of clamps arranged around the chain the latter forces the welt to close contact at all points or places along its length.
- 15 In use, after the shoe has been prepared, the link chain is fitted upon the welt and is held thereto by the small barbs. Then the cement is applied to the welt and to the sole, and the last 20 is inserted. The shoe is then placed on the base, and without allowing the cement to dry the clamps are applied in the manner described to press the welt against the sole, and the work remains clamped in position until the cement is set. The device can be operated without the help 25 of a shoe press, by simply cementing the sole to the inner sole and then afterwards applying cement between the welt and the edge of the sole and then pressing the same together by the clamps as above described.

30 As stated the invention is not limited to the details of the apparatus illustrated and described, but various changes may be made within the scope of the following claims. For example, the 35 finger 20 may be made wider at the inner end, as shown at 20a, to have a longer bearing on the chain.

I claim:

1. A welt press for shoes, comprising a support 40 for the shoe sole, an elongated thin flexible member fitting along upon the welt, and a plurality of pressure clamps arranged around the

periphery of said support and having fingers pressing upon said member at spaced points along the same, to press the welt and sole together, said fingers being adjustable both vertically and horizontally to locate the inner ends thereof at any desired points along said flexible member.

2. A welt press for shoes, comprising a chain adapted to fit upon and along a welt, and means to apply pressure to the chain, to press the welt 10 against the sole of the shoe, the chain having projecting barbs for engagement with the welt.

3. A welt press for shoes comprising a base having an elastic pad therein, a series of pressure devices mounted on and around the periphery of 15 the base, and means extending along and upon the welt of a shoe resting upon the pad to receive the pressure of said devices to press the welt against the sole of the shoe, each pressure device comprising a bolt projecting upwardly 20 from the base, a block adjustable on the bolt, a nut on the bolt, bearing against the block, and an inwardly projecting finger adjustably mounted on the block and adapted to bear at its inner end against said means.

4. A welt press for shoes, comprising a hollow base having an elastic pad therein, a chain extending along and upon the welt of a shoe resting upon the pad, to press the welt against the sole of the shoe, and a series of separate clamps 30 arranged around the outer side wall of the base, each clamp comprising a screw bolt loosely engaging the base and projecting upwardly above the same, a nut screwed on the upper end of the bolt, a block adjustable on the bolt under the 35 nut, and a finger projecting inwardly from the block and bearing at its inner end upon said chain.

5. A welt press as in claim 4, the finger being adjustable lengthwise in the block.

OTTO JACOBUS.
